DIRECTION FINDER INSTALLATION

Albert Troost, Ulm (Donau), Germany, assignor
to Telefunken Gesellschaft fuer drahtlose Tele-
graphie G. m. b. H., Stuttgart, Germany

Application October 23, 1951, Serial No. 252,663

Claims priority, application Germany
October 30, 1950

10 Claims. (Cl. 343—113)

1

The present invention relates to a direction finder installation and a method for ascertaining the operating condition of the parts thereof.

It is an object of the present invention to facilitate a checking of the operating condition of the parts of a direction finder installation.

It is another object of the present invention to ascertain faults in the directional antennas or in the connections thereof.

It is a further object of the present invention to ascertain a break or a short-circuit in the connections to the directional antennas.

It is a still further object of the present invention to ascertain faults of the kind described at the place of the operator which, as a rule, is remote from the directional antennas.

A method according to the present invention comprises in its broadest aspects the steps of generating a high frequency voltage, and coupling the high frequency voltage to the parts of the direction finder installation.

In a preferred embodiment of the present invention a harmonic, preferably the third harmonic, is filtered out of the high frequency voltage and coupled to the parts of the direction finder installation.

A direction finder installation according to the present invention comprises in combination a plurality of directional antennas arranged symmetrically with respect to one another, a goniometer having a plurality of stationary windings arranged symmetrically with respect to one another and being connected, respectively, to the directional antennas, a rotatable winding forming part of the goniometer, means for locally generating a high frequency voltage, and switching means for connecting the stationary windings simultaneously to the generating means whereby the high frequency voltage is applied by the switching means simultaneously to the stationary windings and the directional antennas connected therewith so that the operative condition thereof can be ascertained by rotating the rotatable winding of the goniometer into a position of extremal current response.

In a preferred embodiment of the present invention an amplifier including an oscillating stage is connected to the rotatable winding of the goniometer and the high frequency is generated in the oscillating stage of the amplifier.

Preferably the switching means include stationary contacts connected, respectively, to the terminals of the stationary windings, and movable contacts connected to the oscillating stage of the amplifier. Preferably condensers are in-

2

serted, respectively, between the stationary contacts and the terminals of the stationary windings.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

The only figure is a wiring diagram showing the essential parts of a direction finder installation according to the present invention.

Referring now to the drawing, the direction finder installation comprises a plurality, preferably two directional antennas 1 and 2 such as frames or loops which include with each other an angle of 90°. The antennas 1 and 2 are connected, respectively, over two cables 3 and 4 to the stationary field windings 5 and 6 of a goniometer which include an angle of 90° with each other. The rotatable winding 7 of the goniometer is connected to the tuning condenser 8 which is connected between a cathode and the grid of the first tube 9 of an amplifier. The cables 3 and 4 are only diagrammatically indicated in the drawing and it should be understood that the directional antennas or loops 1 and 2 can be arranged remote from the goniometer, the cables 3 and 4 having in this case a considerable length.

10 is an oscillating or mixing stage, preferably the second oscillator or mixer of the amplifier the first tube 9 of which is connected to the tuning condenser 8 and the rotatable winding 7 of the goniometer. The oscillating or mixing stage 10 generates a high frequency voltage having as a rule a frequency of 70 kilocycles per second which is applied to a cable 11 connected to the movable contacts 12' and 12'' of a switch 12 which is preferably a two-pole double-throw switch having stationary contacts 12a', 12b', 12a'', 12b'' cooperating, respectively, with the movable contacts 12' and 12''. The stationary contact 12a' is connected over a condenser 15 to one terminal of the stationary winding 5, the other terminal of which is connected to the stationary contact 12b' over a condenser 13. The stationary contact 12a'' is connected over a condenser 16 to one terminal of the stationary winding 6, the other terminal of which is connected to the stationary contact 12b'' over a condenser 14.

45 As already mentioned, tube 9 is the input stage

of an amplifier, and tube 10 the oscillator stage of the amplifier. The remainder of the amplifiers is indicated by the dashed block 18. The output of the amplifier is supplied to an indicator 19 which may be any type of indicator known in the art. The entire arrangement including stage 9, oscillator 10, amplifier 18 and indicator 19 comprise the indicator means 17 which is connected to the rotatable winding 7 of the goniometer.

Instead of capacitively coupling the high frequency voltage to the stationary windings 5 and 6 an inductive coupling could be provided. Also, the high frequency voltage could be coupled with the directional antennas by a system of conductors consisting of two coils arranged at right angles to each other and symmetrically with respect to the directional antennas.

The operation of this device is as follows:

If it is intended to ascertain the operative condition of the parts of the direction finder installation, and more particularly of the directional antennas 1 and 2, the cables 3 and 4, and the stationary windings 5 and 6, the switch 12 is closed either to make contact with the stationary contacts 12a' and 12a'' or with the stationary contacts 12b' and 12b''. In either case the high frequency voltage generated by the oscillating stage 10 of the amplifier is coupled with the stationary windings 5 and 6, the cables 3 and 4 and the directional antennas 1 and 2.

Preferably the receiver of the direction finder installation is tuned to a harmonic, preferably the third harmonic, of the high frequency voltage generated by the second oscillating or mixing stage 10. Then the rotatable winding is rotated until an extremal, i. e. a minimum or maximum current response is obtained. If all the parts of the direction finder installation are in good operative condition the extremal, i. e. the maximum or minimum current response of the rotating winding will occur when the latter includes an angle of 45° with each of the stationary windings 5, 6 because in this case the stationary windings are excited equally by the high frequency voltage or the harmonic thereof. If, however, an asymmetry exists, for instance, by the break of a conductor or by a short-circuit, even a high ohmic short-circuit which can be caused by water entering one or both of the cables 3 and 4, the angle deviates from 45°, a deviation to one side indicating a break of a connection and a deviation to the other side indicating a short-circuit. Therefore such faults are rendered easily recognizable. It should be noted that a particular advantage of the present invention consists in that faults of the direction finder installation can be recognized at the working place of the person operating the goniometer so that the operator has not to go as far as the remote place of the directional antennas 1 and 2.

The two positions of the double-throw switch 12 are provided in order to ascertain faults caused by a defect of parts of the stationary windings 5 and/or 6 of the goniometer.

It will be understood that each of the elements described above, or two or more together, may also find a useful application in other types of methods for ascertaining the operative condition of the parts of a direction finder installation differing from the types described above.

While the invention has been illustrated and described as embodied in a direction finder installation, it is not intended to be limited to the details shown, since various modifications and

structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be secured by Letters Patent is:

1. In a direction finder installation, in combination, a plurality of directional antennas arranged symmetrically with respect to one another; a goniometer having a plurality of stationary windings arranged symmetrically with respect to one another and connected, respectively, to said directional antennas; a rotatable winding forming part of said goniometer, said goniometer being arranged remote from said directional antennas; connections connecting, respectively, said stationary windings of said goniometer with said directional antennas; an amplifier connected to said rotatable winding of said goniometer, said amplifier including an oscillating stage; means for generating a high frequency voltage in said oscillating stage of said amplifier; switching means for connecting said stationary windings simultaneously to said generating means, said switching means including stationary contacts connected, respectively, to the terminals of said stationary windings, and movable contacts connected to said oscillating stage of said amplifier; and condensers inserted, respectively, between 40 said stationary contacts and the terminals of said stationary windings whereby the high frequency voltage is applied by said switching means simultaneously to said stationary windings and said directional antennas connected therewith so that the operative condition thereof can be ascertained by rotating said rotatable winding of said goniometer into a position of extreme current response.

2. A system for testing the performance of a direction finder installation including a first and a second directive antenna arranged symmetrically with respect to each other, a goniometer having a pair of relatively stationary windings connected to said first and said second antenna, respectively, as well as a third winding movable with respect to said pair of windings, and indicator means connected to said third winding; said system comprising a local source of high-frequency voltage and connecting means for impressing said high-frequency voltage simultaneously upon both of said stationary windings and both of said antennas, thereby producing in said goniometer an electro-magnetic field whose direction, as ascertained through said indicator means upon rotation of said third winding, is dependent upon the relative impedances of said stationary windings and said antennas, whereby a departure of any of said impedances from normal may be determined from a deviation of said field from a predetermined orientation.

3. A system for testing the performance of a direction finder installation including a first and a second directive antenna arranged symmetrically with respect to each other, a goniometer having a pair of relatively stationary windings

connected to said first and said second antenna, respectively, as well as a third winding movable with respect to said pair of windings, and indicator means connected to said third winding; said system comprising a local source of high-frequency voltage and connecting means for impressing said high-frequency voltage upon a portion of each of said stationary windings and in bucking relation thereto upon another portion of each of said stationary windings in series with the respective one of said antennas, thereby producing in said goniometer an electromagnetic field whose direction, as ascertained through said indicator means upon rotation of said third winding, is dependent upon the relative impedances of said stationary windings and said antennas, whereby a departure of any of said impedances from normal may be determined from a deviation of said field from a predetermined orientation.

4. A system for testing the performance of a direction finder installation including a first and a second directive antenna arranged symmetrically with respect to each other, a goniometer having a pair of relatively stationary windings connected across said first and said second antenna, respectively, as well as a winding movable with respect to said pair of windings, and indicator means connected to said third winding; said system comprising a local source of high-frequency voltage and circuit means for connecting said source between the midpoint of each of said stationary windings and a point intermediate each stationary winding and the respective antenna, thereby producing in said goniometer an electromagnetic field whose direction, as ascertained through said indicator means upon rotation of said third winding, is dependent upon the relative impedances of said stationary windings and said antennas, whereby a departure of any of said impedances from normal may be determined from a deviation of said field from a predetermined orientation.

5. A system for testing the performance of a direction finder installation including a first and a second directive antenna arranged symmetrically with respect to each other, a goniometer having a pair of relatively stationary windings connected across said first and said second antenna, respectively, as well as a third winding movable with respect to said pair of windings, and indicator means connected to said third winding; said system comprising a local source of high-frequency voltage, circuit means connecting an output terminal of said source to the midpoint of each of said stationary windings, and switch means for connecting another output terminal of said source selectively to a point intermediate each antenna and either half of the respective stationary windings, thereby producing in said goniometer an electromagnetic field whose direction, as ascertained through said indicator means upon rotation of said winding, is dependent upon the relative impedance of said stationary windings and said antennas, whereby the presence of a defect in either of said stationary windings and antennas may be determined from a deviation of said field from a predetermined orientation, operation of said switch means to reverse the connection between said source and said winding halves enabling identification of the defective antenna or winding half.

6. In a direction finder installation, in combination, a first and a second directive antenna arranged symmetrically with respect to each

other; a goniometer having a pair of relatively stationary windings connected to said first and said second antenna, respectively, as well as a third winding movable with respect to said pair of windings; indicator means connected to said third winding, said indicator means including an amplifier provided with a mixing stage having oscillator means; and circuit means connecting said oscillator means to both of said stationary windings and both of said antennas in a manner producing in said goniometer an electromagnetic field whose direction, as ascertained through said indicator means upon rotation of said third winding, is dependent upon the relative impedances of said stationary windings and said antennas, whereby a departure of any of said impedances from normal may be determined from a deviation of said field from a predetermined orientation.

7. In a direction finder installation, in combination, a first and a second directive antenna arranged symmetrically with respect to each other; a goniometer having a pair of relatively stationary windings connected to said first and said second antenna, respectively, as well as a third winding movable with respect to said pair of windings; indicator means connected to said third winding, said indicator means including an amplifier provided with a mixing stage, oscillator means in said mixing stage, and an input circuit for said amplifier tuned to a harmonic of the output of said oscillator means; and circuit means connecting said oscillator means to both of said stationary windings and both of said antennas in a manner producing in said goniometer an electromagnetic field whose direction, as ascertained through said indicator means upon rotation of said third winding, is dependent upon the relative impedances of said stationary windings and said antennas, whereby a departure of any of said impedances from normal may be determined from a deviation of said field from a predetermined orientation.

8. A method of testing the performance of a direction finder installation including a first and a second directive antenna arranged symmetrically with respect to each other, a goniometer having a pair of relatively stationary windings connected to said first and said second antenna, respectively, as well as a third winding movable with respect to said pair of windings, and indicator means connected to said third winding; said method comprising the steps of locally generating a high-frequency voltage, applying said voltage simultaneously to both of said stationary windings and both of said antennas in a manner producing in said goniometer an electromagnetic field whose direction is dependent upon the relative impedances of said stationary windings and said antennas, and determining the orientation of said field by rotating said third winding to a position of extreme response of said indicator means.

9. A method of testing the performance of a direction finder installation including a first and a second directive antenna arranged symmetrically with respect to each other, a goniometer having a pair of relatively stationary windings connected to said first and said second antenna, respectively, as well as a third winding movable with respect to said pair of windings, and indicator means connected to said third winding; said method comprising the steps of locally generating a high-frequency voltage producing a first magnetic field in each of said stationary windings by applying said voltage to a portion

thereof, simultaneously producing a second magnetic field of different magnitude from said first field, and in bucking relation thereto, in each of said stationary windings by applying said voltage to another portion thereof in series with the respective antenna, and determining the existence of any off-normal orientation of the resulting magnetic field by rotating said third winding to a position of extreme response of said indicator means.

10. A method of testing the performance of a direction finder installation including a first and a second directive antenna arranged symmetrically with respect to each other, a goniometer having a pair of relatively stationary windings connected to said first and said second antenna, respectively, as well as third winding movable with respect to said pair of windings, and indicator means connected to said third winding; said method comprising the steps of locally generating a high-frequency voltage, producing a first magnetic field in each of said stationary windings by applying said voltage directly to one half of each of said stationary windings, simultaneously producing a second, smaller magnetic field of opposite polarity in each of said station-

ary windings by applying said voltage to the other half of each of said stationary windings in series with the respective antenna, noting the orientation of the resulting magnetic field by 5 rotating said third winding to a position of extreme response of said indicator means, applying said voltage directly to said other half of each of said stationary windings and, simultaneously therewith, to said one half of each of said stationary windings in series with said respective antenna, noting the orientation of the resulting magnetic field by rotating said third winding to a position of extreme response of said indicator means, and comparing said orientations with each other and with a predetermined reference direction.
